UNITED STATES PATENT OFFICE.

CHARLES ALBERT KUSTER, OF ELMHURST, NEW YORK, ASSIGNOR TO TONOH-METAL PRODUCING COMPANY, A COPARTNERSHIP COMPOSED OF RUDOLPH KLEINMAN, JULES BLOOM, AND ISIDOR BLOOM, ALL OF NEW YORK, N. Y.

DESIGN FOR A BRACKET BACK FOR LIGHTING FIXTURES.

Application filed January 26, 1925. Serial No. 12,141. Term of patent 3½ years.

To all whom it may concern:

Be it known that I, CHARLES ALBERT KUSTER, a citizen of the United States, residing at Elmhurst, L. I., in the county of Queens and State of New York, have invented a new, original, and ornamental Design for Bracket Backs for Lighting Fixtures, of which the following is a specification, reference being had to the accompanying drawing, forming part thereof.

Fig. 1 is a top plan view; and
Fig. 2 is a front elevation showing my new design.

I claim:

The ornamental design for a bracket back for lighting fixtures, as shown.

CHARLES ALBERT KUSTER.
